J. J. Geisler

Attorney

UNITED STATES PATENT OFFICE.

GUSTAV CRAMER, OF PORTLAND, OREGON.

TWO-FINGER RING.

Application filed November 23, 1926. Serial No. 150,221.

My invention relates to finger rings which are designed to carry, as a setting, a large jewel. This type of finger ring is frequently desirable, but the ordinary finger ring is impractical for such purpose.

A large jewel worn on one finger tends to cause the ring to slip on the finger, by the weight of the jewel; and furthermore, a large jewel carried by a single finger ring would require a very high setting, and thus would be bulky and inartistic.

The object of my invention is to provide a two finger ring on which a large jewel may be mounted without causing any inconvenience to the wearer of the ring.

I attain my object by a ring comprising a bezel and two bands, one thereof hinged to each of the opposite sides of the bezel, so that said bands are adapted to be placed, respectively, on two adjacent fingers, of hands varying in width; and so to permit free and unhampered movement of each finger relatively to the other.

My improvement permits a relatively low setting, also prevents the weight of the jewel causing the ring to slip down on the finger, and thus get the setting in an inconvenient position. Trials of my improved finger ring have demonstrated that it may be worn without any inconvenience; also that it does not limit the separation of the fingers nor impede their relative play or movement. For example, in the demonstrating trials with my finger ring in one instance, it was worn while writing, in another while playing the piano.

Further details of my improved finger ring are hereinafter described with reference to the accompanying drawings, in which:

Fig. 1 shows a perspective view of my finger ring and how it will appear when worn on the hand, the ring being shown in full lines, and the hand in dotted lines;

Fig. 2 shows a section taken on the line 2-2 of Fig. 3, looking in the direction of the arrows, the jewel having been removed and shows the details of construction of the joints by which the bands are connected to the bezel of the ring.

Fig. 3 shows a section taken on the line 3-3 of Fig. 2 looking in the direction of the arrows and shows further details of the joints by which the bands are connected to the bezel of the ring;

Fig. 4 shows a side elevation of my ring and how the setting of the jewel is lowered and held between the fingers;

Fig. 5 shows a top plan view of my ring; Fig. 6 shows a side elevation of my ring and the position of the bands when one finger is raised higher than the other; and

Fig. 7 shows the details of construction of the joints by which the bands are connected to the bezel.

My finger ring comprises a bezel or crown element *a* for mounting the jewel, and two bands *b* and *c* which are joined to the bezel by oppositely placed outstanding lugs *d* and *e*. Each band is provided with a housing *f* and *g* in which the lugs *d* and *e* are rotatably fastened by pins *h* and *i*, thus forming a tongue and groove hinge.

The exterior portion of the housings *f* and *g* are closed as at *j* and *k*, thereby limiting the movement of the bands so that the bands will always be held in a more or less convenient position for slipping over two adjacent fingers.

Though any convenient means for joining the bands to the bezel may be used, the mode shown in the drawings and herein described is preferable, since in a piece of jewelry, the construction of the hinge must necessarily be light and the metals used, as gold for example, are soft and by providing a tongue and groove hinge, the lugs *d* and *e* are supported against lateral wear and there will be no tendency for the bands to become loose and "wobbly."

I claim:

1. A two finger ring comprising a crown element and a band hinged to each of the opposite sides thereof and adapted to lateral movement in a transverse central plane of said crown element, whereby said bands are adapted to be placed respectively on two adjacent fingers of hands varying in width and permit movement of each finger relative to the other.

2. A two finger ring comprising a bezel provided with oppositely projecting hinged lugs, two bands each provided with a socket adapted to receive and have said hinge lugs hinged therein, whereby said bands are adapted to be placed respectively on two adjacent fingers of hands varying in width, said sockets of the bands substantially concealing said lugs of the bezel, but permitting movement of either finger relative to the other.

GUSTAV CRAMER.
